UNITED STATES PATENT OFFICE

2,516,175

CHAIN BREAKER-PLATE FEED STRUCTURE
FOR ROTARY CRUSHERSCharles M. Bindner, Normandy, Mo., assignor to
Dixie Machinery Manufacturing Company, St.
Louis, Mo., a corporation of Missouri

Application March 8, 1947, Serial No. 733,337

2 Claims. (Cl. 241—186)

1

This invention relates to rotary crushers, and more particularly to rotary hammer crushers for crushing stone and similar materials, and is an improvement upon the crusher disclosed in Patent No. 1,605,181.

Among the several objects of the invention may be noted the provision of an improved chain breaker-plate feed-structure for crushers of the rotary hammer type with movable and adjustable breaker plates for crushing materials to consistently finer and more uniform sizes than heretofore feasible; the provision of a structure of the class described wherein the moving chain breaker-plate is more positively held in a straight-run alignment between platen and cage parts below the impact region so as better to withstand without distortion the severe impact of the hammers and also to prevent escape of improperly crushed material; and the provision of a crusher having the above desirable features which is economical to construct in a rugged form and which has long life. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a side elevation of the crusher, excepting its flywheel, being taken on line 1—1 of Fig. 3;

Fig. 2 is a vertical section taken on line 2—2 of Fig. 1, the central rotary parts being omitted, better to illustrate the invention;

Fig. 3 is a vertical section taken on line 3—3 of Fig. 2, but illustrating the rotary parts in position;

Fig. 4 is a fragmentary plan view of the base of the machine, being taken on line 4—4 of Fig. 1; and,

Fig. 5 is a vertical detail section taken on line 5—5 of Fig. 4.

Similar reference characters indicate corresponding parts throughout the several views of the drawings.

The crusher shown in Patent 1,605,181 is subject to some disadvantages in that amounts of improperly graded materials may pass out of the crushing chamber without having passed through its cage bars. This is because under some cir-

2

cumstances a substantial gap for the escape of material occurs between the ends of the cage-bar section and the curved portion of the breaker plate where it passes over the lower sprockets.

5 Furthermore, in the patented structure an essentially cantilever, rather than a beam type of support for the backing plate serves to provide the reaction against crushing forces, and a beam type of support is preferable.

10 By means of the present invention the backing plate for the movable breakers responds to crushing forces as a simple sturdy beam. Also, the arrangement between the ends of the cage-bar section is in a more advantageous position both 15 with respect to the movable breaker plates and the backing plate, thereby preventing undesirable passage of improperly crushed material.

Referring now more particularly to Fig. 1, there is shown at numeral 1 a base which, as shown 20 in Fig. 3, is in the form of a hollow horizontal frame-like foundation or bed having front and back walls 3 and side walls 5 (see also Fig. 2).

Upon the bed 1 is a superstructure 7 consisting of side walls 9 from which extend lateral supports 11 for bearings 13. The superstructure 7 has a front wall 15 in which is an openable door 17. The rear of the superstructure 7 is generally open, which provides an inlet 19 at the top. Behind the inlet 19 and enclosing the back of the superstructure is a movable breaker plate assembly indicated generally at numeral 21. This assembly will be described in detail below.

Supported in the bearings 13 is a shaft 23 carrying an outside flywheel 2. Upon shaft 23 are keyed the usual discs 25 for supporting swinging hammers 27 on pivots 29. Additional openings 31 are provided on variable centers for adjustably positioning the pivots 29 so that the radii of the hammer action may be changed from time to time as desired. Further details of these hammer supports are unnecessary, being known. The inside of the superstructure 7 is suitably lined by means of wear plates shown but not indexed in detail, since the provision of such wear plates 45 is also known.

On the insides of the side walls 9 are bolted arecuate shelves 33 for supporting along the peripheries of the hammers lateral cage-bar sections 35 and 36. The last cage-bar section 36 (at the left in Fig. 3) is of special form. This section, instead of being open as are the sections 35, may be solid and is formed at its upper rearward edge as an acute angle 37. The significance of this will appear below.

55 Detailed reference will now be made to the

breaker plate assembly 21. Between the side walls 9 is pivoted a backing platen 39, which has suitable side ribs 41 and cross ribs 43. This platen is pivoted on an upper crossbolt or shaft 45 which passes through the side walls 9. In the side ribs 41 are elongate openings 47 for the reception of round supporting bars or cross-shafts 49 and 51. These bars also respectively pass through elongate horizontal openings 53 formed in the side walls 9. It will therefore be seen that if the bars 49 are adjusted forward or backward, the angular position of the platen 39 will be adjusted accordingly, with the crossbolt 45 as a pivot center.

In order to adjust the upper supporting bar 49 along the elongate openings 53, it is caused to pass through eyes 55 in the rear ends of upper tension bars or straps 57. These straps respectively pass forward outside of the respective sides 9 and within the respective bearings 13. At their front ends, the bars 57 are formed as round bolts 59, passing through openings 61 in lugs 63. The latter are attached to extension pads 65 from the sides 9 and from the bearing supports 11. Both bolts 59 are threaded beyond the lugs 63 and are provided with a lock nut arrangement 67 for adjustment purposes.

Similarly, the lower supporting bar 51 is movable back and forth in its horizontal slots 53. This is accomplished by surrounding parts of the bar 51 outside of the sides 9 with eyes 69. These eyes are on the rear ends of forwardly extending rods 71 which pass through openings in the bearing supports 11, being threaded at their forward ends and provided with lock nut adjusting nuts 73 for adjusting purposes.

From the above it will be clear that by loosening the lock nuts 67 and 73, the tension members 57 and 51 may be moved back and forth to adjust the angular position of platen 39.

Pivoted outside of the sides 9 and to the upper bolt 45 are adjusting side arms 75. The pivoting collars for this purpose are shown at 77. The bolt 45 is threaded outside of the collar 77 for the reception of lock nut 79, whereby, after an adjustment of the arms 75, the lock nut 79 may be tightened to aid in holding the adjustment by reaction against the sides 9. At 81 these side arms are provided with relatively large openings 83 loosely to accommodate the cross-shaft 49. Where the cross-shaft 49 emerges from the openings 83, it is threaded and provided with outside lock nuts 85 having spanner wrench openings 86. Between the arms 75 and sides 9 are the eyes 55. Thus by tightening the nuts 85 the bar 49 may be put into tension, thus clamping the side arms 75 against the eyes 55, forcing the latter against the sides 9 of the superstructure and aiding the tension members 57 in holding the bar 49. Thus the shaft 49 is held in proper adjusted position to support the backing platen 39.

At a lower elevation the arms 75 are provided with additional elongate openings 87 which have accurately-machined pads 88 engaging the lower bar 51. The arms 75 are adjusted in position by adjusting the position of bar 51 from rods 71. It will be noted from Fig. 2 that washers 89 are employed directly inside of the arms 75 at shaft 51. Outside of the arms 75 at this point are the eyes 69 of the rods 71. Outside of these eyes the shaft 51 is provided with spanner nuts 91 whereby, on opposite sides of the machine, the washers 89, arms 75 and eyes 69 may be squeezed towards the respective sides 9, thus tightly clamping the shaft 51 and the side arms 75. Clamping is effected

after adjustment from rods 71. The spanner openings in nuts 91 are shown at 92.

At their lower ends the arms 75 are provided with an additional set of openings 93, having pads 95 engaging gudgeons 97 of outside bearings 99. In extending to their lowermost locations, the arms 75 pass through openings 101 in parts of the bed 1 (see Figs. 4 and 5). Thus any adjustment of the arms 75 results in adjustments of the positions of the bearings 99.

The bearings 99 slide in guides 103 which are formed in parts attached to the lower bed 1. The bearings carry threaded stems 105 passing through openings 107, by means of which they may be locked by means of lock nuts 109. The bearings 99 support a shaft 111 which extends through the bed 1 and upon which shaft are fixed inside sprocket wheels 113. The shaft 111 passes across the machine through elongate openings 116 in the side walls 9.

Cooperating with the sprockets 113 is a linked chain of wear resistant breaker plates 117. These have outside flat surfaces and underneath are formed with pockets 114 (see Fig. 4) to cooperate with the sprocket teeth. One reach 119 of the breaker chain extends upward over the front face of the backing platen 39. The other reach 121 extends upward behind the platen. The upper end of the chain passes over wheels 123 located upon an upper shaft 125. Shaft 125 is carried in bearings 127. The bearings 127 slide in sloping guides 129 at the upper rear part of the superstructure 7. The positions of these bearings are adjusted by means of adjusting studs 131 threaded through them.

Referring more particularly to Fig. 3, it will be seen that the acute angled portion 37 of the cage-bar section 36 lies more or less tangent to the section of the forward reach of the chain of breaker plates 117 where the plates have a straight-line motion and where they are well supported by a portion of the backing platen 39, that is, opposite to the holding bar 51 and above the lower sprockets 113. On the inner faces of the sides 9 are guide strips 133 which overhang the ends of the breaker plates. These strips 133 at their lower ends are curved in a tangent relationship with respect to the member 36, as shown at 135. The strips are adjustable in position as indicated at slotted connections 136. They avoid clogging at the ends of the breaker plates 117.

Operation is as follows:

The shaft 23 is rotated from a suitable prime mover coupled at 4, the flywheel 2 keeping the action steady. The hammers then rotate anti-clockwise (Fig. 3). The lower sprocket shaft 111 is slowly driven by means of a separate drive coupled at 6. The chain of breaker plates moves in the direction shown by the arrow in Fig. 3. The hammers perform the initial main crushing operation on the raw material at region C, which is above the lower bar 51 and below bar 49. Thus the backing platen 39 is strongly supported above and below this region C. This makes an extremely rigid construction, since the primary crushing region of the chain 117 is supported by the backing platen 39 as a simple beam. Furthermore, this primary crushing region C is at a substantial distance from the lower sprocket 113, thus assuring that the breaker plate chain at this region is not in a loose condition of approach to the sprockets 113. Also, by having the shaft 111, sprockets 113 and bearings 99 down in the bed portion 1, there is ample space between the

sprockets and the primary crushing portion C for the best arrangement of the sharply angled member 36. The latter forms an efficient seal against loss of material into the outlet below the bed 1. Heretofore, the last cage bar has been adjacent to the lower sprockets 113. The unsteady action of the chain of breaker plates at this point, without a member such as 36, has allowed the escape of a substantial amount of material, which is avoided by means of the present construction.

After operation has continued a substantial period of time, the breaker plates of course wear. In order to take up the increased opening which might occur at point 37, adjustments may be made. These are brought about as follows:

Nuts 85, 91, 67, 73, 79 and 109 are loosened. The adjusting bar members 57 and 71 are drawn forward a proper amount which causes simultaneous swinging of the backing platen 39 and the breaker chain 117. It will be noted that adjusting motion of the shafts 49 and 51 not only adjusts the platen, but also the arms 75 which control the position of shaft 111. This in turn keeps the position of the chain of plates 117 in proper relation to the platen 39. The pads 88 and 95 maintain an accurate relationship between the shafts 51 and 111. Therefore the platen 39 and the chain of breaker plates 117 are accurately related. It may be noted that the openings 83 in the arms 75 are substantially larger than the diameter of bar 49. This is because in rugged apparatus of this type it would be impracticable to maintain the requisite accuracy between three sets of pads of the nature of pads 88 and 95.

After the proper adjustments have been made, all of the said nuts 85, 91, 109, 67, 79 and 73 are locked tightly so as positively to hold all of the parts in their adjusted positions.

It should be noted in connection with the bars 49 and 51 that they are strongly held in definite positions by the clamping actions of the nuts 85 and 91 of various parts against the sides 9. In the case of bar 49 these parts are the arms 75, and eyes 55. In the case of shaft 51, these parts are the eyes 69, arms 75 and spacer washers 89.

In view of the above, it will be clear that material which is introduced into the machine at opening 19 is initially crushed at the well-supported region C. That part of it that is small enough passes out through the cage-bar sections 35. Any that is too large is sent around through successive cycles of the hammers 21 until it is crushed down to the size that will pass the cage bars 35. The properly sized and crushed material emerging from the bars 35 drops down through the hollow bed 1 into a suitable outlet.

It will be seen that, of the group of cage bars 35 and 36, the end bar 36 extends to a point of tangent cooperation between the hammers 47 and the chain of breaker plates 119. This bar 36 being of wedge form as shown at 37, with one side lying along the chain of breaker plates and the other side extending just outside the paths of the hammers as they leave the tangent region, substantially prevents escape of material at this point and inhibits clogging, acting somewhat as a scraper with respect to the breaker plates. Also, the fact that the chain of breaker plates is backed up by the lower extension of the platen 39 just under the bar 36 on all sides, constrains the paths of the breaker plates as they leave the tangent region. Thus the favorable conditions

of initial adjustments are positively maintained over long periods, regardless of slack that may occur between adjustments in the chain of plates 119.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A rotary crusher comprising a bed in the form of a hollow frame, an enclosing superstructure on the bed, rotary hammers in the superstructure swinging in paths above the bed, said superstructure having an inlet above the hammers, a shaft across the inlet carrying a first group of sprockets, a shaft across the bed carrying a second group of sprockets substantially below the hammers, a chain of movable breaker plates having a reach between the groups of sprockets and passing the paths of the hammers at a tangent region, a breaker platen pivotally supported on the superstructure and located behind said reach of breaker plates, an arcuate group of cage bars below the paths of the hammers and extending into wedge relationship between said reach of breaker plates and the hammer paths just under said tangent region, said platen extending behind said reach of breaker plates from points above the tangent region to points below the tangent region and for a distance directly opposite said wedge shape of the cage bars, supporting shafts movable in the superstructure and supporting said platen at points above and below the tangent region, means for adjusting the positions of said shafts on the superstructure, arms pivoted outside of the superstructure on the same pivot as that of the platen and extending downward, bearings for said sprocket shaft which is in the bed, said arms controlling the positions of the last-named shaft, at least one of the shafts which adjustably supports the platen extending through said arms to control their positions simultaneously with the control of the platen position, whereby the position of said reach of breaker plates is also simultaneously controlled.

2. A rotary crusher comprising an enclosure formed by an upper superstructure and by a supporting bed portion forming an elevated support, rotary swinging hammers in the superstructure swinging in paths above the bed portion, said superstructure having an inlet above the hammers, a shaft across the inlet carrying a first group of wheels, a shaft across the bed portion carrying a second group of wheels in said bed portion entirely below the swing of the hammers in the superstructure, a chain of movable breaker plates having a reach between the groups of wheels and passing the paths of the hammers at a tangent impact region, an adjustable breaker platen pivotally supported on the superstructure and located behind said reach of breaker plates, an arcuate group of cage bars below the hammer paths one of which extends to and forms a chain guide at a location under the tangent region at said reach of breaker plates and entirely above the lower group of wheels, said platen extending behind said reach of breaker plates from points substantially above the tangent region to points substantially below the tangent region and below

said chain guide location but entirely above said second group of wheels, whereby said reach of breaker plates is positively held in a substantial straight run through the space between the guiding platen and guiding cage parts, and a pair of adjustably movable cross-shafts in the superstructure and supporting said platen at portions closely adjacent to the upper and lower parts of the tangent region.

CHARLES M. BINDNER. 10
